DIE FOR COLLAR FOLDING MACHINES

Howard C. Underwood and Edward B. Roby, New
York, N. Y.

Application October 5, 1934, Serial No. 747,009

3 Claims. (Cl. 223—38)

Among the principal objects which the present invention has in view are:—to fold the edges of a collar by utilization of male and female dies; to apply heat simultaneously during the folding operation; to utilize a machine with interchangeable parts for various sizes and patterns of the article being manufactured; to be enabled to easily remove the article after the edges have been folded to avoid necessity of any unfolding of the edges to remove the article; to utilize the folded edges as means assisting removal of the article from the female die; to secure simplicity of construction and operation; and to obtain other advantages and results as may be brought out in the following description.

In the drawings:

Figure 1 is a top plan view of the machine and having one edge turning mechanism thereon;

Figure 2 is a plan view of the collar or blank placed in the machine ready to be operated on, the upper or plunger die being omitted for greater clarity;

Figure 3 is a transverse sectional view shown as taken on line 3—3 of Figure 2, and showing the relative position of the plunger die in the preparatory stage of the operation ready for performing the first or upstanding fold of the one edge of a collar;

Figures 4 and 5 are similar views and showing other stages of the operation, Figure 4 showing the upstanding fold performed by the plunger die and Figure 5 showing the inturned fold by the sliding or folding die sections;

Figures 6 and 7 are plan views of the sliding or folding die sections;

Figure 8 is a plan view of the collar after it has been folded by and removed from the machine;

Figure 9 is a perspective view of one corner portion of the collar after completion of the initial or upstanding fold;

Figure 10 is a plan view of a machine similar to Figure 1 and utilized to produce the end folds upon the article;

Figure 11 is a longitudinal sectional view shown as taken on line 11—11 of Figure 10 showing the end folds completed;

Figure 12 is a plan view of a collar and die before the end folds of the collar have been made; and

Figures 13, 14, 15, and 16 show end portions of the article in stages of the folding operations being performed, thereon particularly illustrating the stages in folding the end edges of the article or collar.

As seen in the drawings the immediate purpose of the present invention is to provide mechanical means to fold the hem edges of collars for men's wear, and particularly the hem edges of collars known as "semi-soft" collars which in use are permanently attached to shirts. The blanks or shapes 20 from which the collars are made are cut in accordance with any desired method in accordance with the design shown in Figure 6 of the drawings. These blanks or shapes 20 are placed within the upper part of a female die, that is, within opposed female positioning blocks 21, 21 shaped to freely receive the same, these blocks being replaceable for others of different shape to enable the machine to operate upon different styles of collars. These blocks 21, 21 are also adjustable toward and away from each other for enabling the same blocks to position any desired neck-band size of collar.

Below blocks 21, 21 is the lower female or forming member 22 of the female die, the cavity portion 23 of which is of appropriate contour or shape to correspond to the desired resultant contour or shape desired for that part of the blank after folding of the blank 20. The female die cavity accordingly comprises a lower portion 23 smaller than the corresponding upper portion or opening of the positioning blocks. In the construction of Figure 1, the positioning edges of the blocks 21 and the cavity of the lower member 22 register with each other except at one longitudinal edge, at which, by virtue of the smaller size of the cavity, the die provides therein on member 22 an upper shoulder 24 upon which an edge of the blank will rest when first introduced into the positioning blocks as shown in Figure 3. It is this edge or margin of the blank resting upon the shoulder 24 which is to be folded.

For effecting the first fold, an upper or plunger die 25 is provided of size and shape to substantially overlie the length and breadth of the collar except for the longitudinal margin overlying said shoulder 24. Furthermore said plunger die 25 preferably substantially fits the cavity 23 of the die member 22, and consequently by depressing the blank into the cavity as shown in Figure 4, by said plunger die, the protruding longitudinal margin of the blank bends upwardly. This bending is herein referred to as the first fold.

While the blank 20 is still within the cavity 23 of the forming die 21—22, and yet under the holding influence of the depressed plunger die, sliding die sections 26, provided for that pur-

pose are actuated inwardly of the cavity from over said shoulder 24, thereby performing a second fold upon the material of the blank. The margin is accordingly thus folded back upon the 5 body portion of the blank to be later stitched and form a hem. In making this hem fold, a thin portion 27 of the pressure or male die lying flatwise upon the body portion of the blank has its marginal edge beneath the turned-in margin of 10 the blank. Consequently, as the plunger die is raised, the blank "hangs" on the same and is withdrawn with it from the female die. Furthermore, since the folding has been performed only at one longitudinal edge, the operator may very 15 conveniently "unhook" the blank from the upper die by a simple sliding movement of the blank.

In referring above to the folding of the longitudinal edge, we also include folding the tip at the opposite ends of said edge. This is accomplished, as will be readily appreciated from 20 the above discussion, by shaping shoulder 24 to underlie the tip and by shaping the sliding sections 26 with angular end portions 28, diverging in relation to the direction of folding movement 25 so as to provide corners which avoid interference with the tips in retracted position of the sliding die sections but which will advance to overlie the tips as the said sections are slid, as clearly indicated in Figures 6 and 7.

30 It will be further noted that as the fold lines of the tips converge toward the longitudinal folded edge of the blank, they form no hindrance to removal or "unhooking" of the blank from the upper die. While the folding of the tips has of 35 necessity been described separately from the folding of the longitudinal edge from tip to tip, it will be appreciated that the folding of edge and tips is a single operation for effecting the up-standing fold and again a single operation for 40 effecting the in-turned fold.

After removal of the blank 20, folded at its longitudinal edge and tips, said blank is acted upon in a second machine for bending the end edges of the collar into a hem fold. We prefer 45 to perform this end folding in a separate machine, for the reason that the end edges converge in a direction away from the longitudinally folded edge, and therefore if folded at the same time as the longitudinal edge, would prevent removal of 50 the blank from the die without partly unfolding the blank. Accordingly the blank is removed to the second machine of Figure 10 likewise equipped with female positioning blocks 21', 21' having thereunder a female forming die 22' with 55 cavity 23' for receiving the blank and effecting an upstanding end fold of an end margin overlying a shoulder 24' by depression of a plunger die 25' as shown in Figures 11 and 12. Thereafter, sliding sections 26', one at each end of the 60 blank, are slid toward each other and bend the end margins of the blank inwardly over the thin portion 27' of the plunger die to be subsequently sewn to form the hems on those edges of the collar. Since there is a divergence of the 65 folded margins, the folded blank, after withdrawal from the female die by "hanging" on the upper die, may be slid readily off of the latter without necessitating an unfolding of the blank.

During the performance of the above described operations of forming the longitudinal edge and end hems it is preferable that the folds remain intact after removing the blank 20 from the plunger dies 25 and 25'. To this end and simultaneously with the lowering of the plunger dies heat is applied to the blanks by virtue of heating the forming dies 22 and 22', the source of supplying the heat thereto not being shown, but fully described and clearly shown in Patent 10 No. 1,600,364.

While the functions of the machines employed are deemed clear from the foregoing, the operating mechanism therefor are disclosed in prior Patent No. 1,600,364 to E. B. Roby one of the co-inventors herein, to which patent cross-reference is here made. When the several operations are completed it will be noted that the hem edges will be disposed as seen in Figures 15 and 16 of the drawings. It also is to be noted that 20 after the hem edges are folded and pressed by the machine, the article or collar is then delivered to a stitching machine when tape and hem stitches may then be applied in the usual manner, after which the collar is then permanently attached to 25 a shirt.

We claim:

1. A machine as characterized comprising in combination, a fixed female die having a stepped cavity, an upper die having a thin portion adapted to be introduced flatwise into said cavity, and means slidable laterally into the cavity of the female die entirely above the level of said thin portion for turning the margin of a blank over at least one edge of the thin portion of the upper 35 die with the die in said cavity, said blank thereafter being free to slide from said thin portion upon separation of said dies.

2. A machine as characterized comprising in combination, a fixed female die having a stepped cavity, an upper die having a thin portion adapted to be introduced flatwise into said cavity, and sliding die sections slidable laterally into the cavity of the female die entirely above the level of said thin portion for turning the margin of a 45 blank over at least one edge of the thin portion of the upper die with the die in said lower portion in said cavity and free to slide from said thin portion upon separation of said dies.

3. A machine as characterized comprising in combination, a fixed female die having a stepped cavity, an upper die having a thin portion adapted to be introduced flatwise into the lower portion of said cavity, and sliding die sections slidable laterally into the cavity of the female die entirely above the level of said thin portion for turning the margin of a blank over at least one edge of the thin portion of the upper die with the die in said lower portion of said cavity and free to slide from said thin portion upon separation of said dies, and said sliding die sections being provided with angular end portions whereby during operation of folding the longitudinal edges of the blank corner tips to the blank will be accomplished.

H. C. UNDERWOOD.
EDWARD B. ROBY.
